(57) **CLAIM**

I claim the ornamental design for a liner dispenser, as shown and described.

DESCRIPTION

FIG. 1 is top perspective view of a liner dispenser.

FIG. 2 is a left side elevation view thereof.

FIG. 3 is a right side elevation view thereof.

FIG. 4 is a front end elevation view thereof.

FIG. 5 is a rear end elevation view thereof.

FIG. 6 is a top plan view thereof; and,

FIG. 7 is a bottom plan view thereof.

The broken lines in the drawings, and the unshaded areas adjacent to them, depict portions of the liner dispenser that form no part of the claimed design.

1 Claim, 4 Drawing Sheets
